UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,137,121.

Specification of Letters Patent. Patented Apr. 27, 1915.

Application filed December 29, 1910. Serial No. 599,874.

To all whom it may concern:

Be it known that I, JOHN L. CREVELING, a resident of the city, county, and State of New York, have invented certain new and useful Improvements in Electric Regulation, as set forth in the annexed specification and drawing, forming a part thereof.

My invention pertains to that class of electric regulation wherein it is desired to automatically govern a generator in a predetermined manner.

As my invention is particularly applicable to those systems wherein a generator, driven at variable speed is used to charge a storage battery and operate lamps or other translating devices, it will be described with reference to such a system.

Figure 1 is a diagrammatic representation of one type of such system embodying the essentials of my invention. Fig. 2 is a modified form of system embodying the essentials of my invention.

In the drawing, 1 represents a dynamo or generator provided with the usual field coil 2, having in series therewith a field controlling element 3, in this instance indicated as a rheostat of the carbon pile variety. From the dynamo 1, the positive lead 4 is carried to the positive side of the storage battery 5 and lamps or translating devices 6, both of which have their negative terminals carried to the negative lead 7 which is shown in Fig. 1 as having the solenoid 8 in series therewith. In Fig. 2, the branch from the positive lead 4 to the battery is shown as having in series therewith the solenoid 9. The only difference in the arrangements shown in Figs. 1 and 2 is that in Fig. 1 the solenoid 8 carries the entire generator output to the battery and lamps, while in Fig. 2, the solenoid 9 carries only the battery current. The carbon pile 3 has its resistance controlled by the pivoted lever 10, normally drawn in an upward direction as by the adjustable spring 11 in such manner as to tend to compress the pile 3 and lower the resistance thereof. The lever 10 is provided at one extremity with the core of magnetic material 12 surrounded by the solenoid 13 in shunt across the leads 4 and 7, or in shunt across that portion of the system upon which it is desired to maintain a constant voltage throughout speed changes of the generator. The spring 11 is carried by the adjusting screw

14, which, in turn is carried upon the lever 15, pivoted as at 16 and normally drawn in an upward direction as by adjustable spring 17, tending to hold the lever in contact with the adjustable limiting screw 18. The lever 15 is provided at one end with the core of magnetic material 19, so arranged as to be surrounded by the solenoid 8 in Fig. 1 or the solenoid 9 in Fig. 2, in such manner that excitation of the solenoid tends to depress the lever 15 against the action of spring 17 and weaken the upward pulling effect of the spring 11 upon the lever 10, in such manner as to cause less opposition to be overcome by the coil 13 in increasing the resistance of the member 3 in such manner, that the voltage necessary across the coil 13 in order to make it respond and keep the generator voltage from rising upon an increase in speed will be lessened by excitation of the series solenoid when sufficient to draw its core 19 downwardly against spring 17.

A practical operation of my invention is substantially as follows:—With the generator running, in the system shown in Fig. 1, current will flow through the field 2 and resistance 3 so as to excite the generator in a well-known manner, and if the generator voltage be sufficient, current will flow through the lead 4, storage battery 5 and lamps or translating devices 6 to the lead 7 and return to the generator through coil 8. Current will also flow from the lead 4 to the lead 7 through the coil 13 and with the lever 15 held against the stop 18, I so adjust the spring 11 that when the voltage across the mains or across any point of the circuit that the solenoid 13 may be connected and which it is desired to hold from having impressed thereon greater than a predetermined voltage, reaches a certain voltage above which it is desired to prevent any excess, the current in the coil 13 will be sufficient to draw the core 12 downwardly against the action of spring 11 and increase the resistance 3 in such manner as to prevent the generator voltage from rising above this predetermined point. I then adjust the spring 17 in such manner, that if this predetermined voltage for which the regulator has been set to hold the generator from exceeding throughout changes in speed, shall tend to cause too great a current to flow through the main circuit and thus through

the solenoid 8, the said solenoid will cause the core 19 to be drawn downwardly against the action of spring 17 and the tension of the spring 11 thus weakened in such manner 5 as to readjust the said spring 11 so to speak for a lower voltage across the coil 13, which voltage the coil 13 will hold constant throughout speed changes of the generator.

The operation of the system shown in 10 Fig. 2 is the same as that described with regard to Fig. 1, with the exception that the current flowing to the battery through the solenoid 19 instead of the current in the main circuit as in Fig. 1, governs the adjustment of the spring 11 through its action upon the lever 15. Thus it will be obvious 15 that I have produced a system wherein the generator is automatically governed to maintain a substantially constant voltage 20 throughout changes in speed or tendencies of its voltage to vary beyond a certain limit and that I have provided means whereby this voltage which shall be held constant throughout speed changes is varied by the 25 current flowing in a portion of the system wherein it is desired to prevent the current exceeding a predetermined amount.

I do not wish in any way to limit myself 30 to the exact details of construction and operation above set forth as a mere diagrammatic representation of one form of employment of my invention, as wide departure may be made within the scope of said invention and is set forth in the following 35 claims:—

1. Means for regulating a generator comprehending voltage varying means; means for operating the same responsive to voltage fluctuations; and means for adjusting the 40 operation of said last-named means adapted to be actuated when the current produced by the generator exceeds a predetermined limit.

2. Means for regulating a generator comprehending means for varying the voltage thereof; means for controlling said voltage varying means responsive to voltage fluctuations; and means for adjusting the effect produced by said voltage responsive means depending upon current fluctuations and adapted to be actuated when the current produced by the generator exceeds a predetermined limit.

3. Means for regulating a generator comprehending regulating means responsive to voltage fluctuations, adjustable means for controlling the same and means for changing the adjustment thereof responsive to current fluctuations beyond a predetermined limit.

60 4. Means for regulating a generator comprehending a voltage operated regulator therefor, means for adjusting the same and means for varying the adjustment thereof

depending upon current fluctuations beyond a predetermined limit. 65

5. Means for regulating a generator comprehending a regulating element, means for operating the same responsive to voltage fluctuations comprising resilient means and means for varying the effect of said resilient 70 means depending upon current fluctuations beyond a predetermined finite limit.

6. The combination with a generator; a regulator therefor; a supply circuit; and means for regulating the generator depending 75 upon the voltage across the supply circuit; of means for adjusting the voltage to be held across the supply circuit dependent upon the current produced by the generator and actuated when the current in the circuit 80 rises above a predetermined limit.

7. The combination with a generator of means for regulating the same comprehending a regulating element, voltage operated 85 means for controlling the regulating effect thereof, resilient means for coöperating with said voltage operated means and current affected means for adjusting the said resilient means to prevent the generator current exceeding a predetermined limit. 90

8. The combination with a source of variable electromotive force, of means for controlling said electromotive force in response to voltage fluctuations and means for adjusting the voltage responsive means affected by 95 current fluctuations above a predetermined value only.

9. The combination with a source of electromotive force tending to vary, of voltage 100 operated means for holding said electromotive force substantially constant throughout tendencies to vary and current responsive means for adjusting the value of electromotive force to be held constant affected by current fluctuations beyond a predetermined 105 value.

10. The combination with a generator and a supply circuit, of means for regulating the generator to hold its voltage constant and means coöperating therewith to adjust the 110 voltage to be held constant and means for operating the same affected by excess in current above a predetermined value only.

11. The combination with a generator driven at variable speeds, means responsive 115 to voltage fluctuations for holding the generator voltage constant throughout speed changes and means for adjusting the voltage to be held constant of means for operating the adjusting means to hold the voltage below that necessary to cause current due thereto to exceed a predetermined value. 120
